UNITED STATES PATENT OFFICE.

HARRY M. BLAETZ, OF PHILADELPHIA, PENNSYLVANIA, ASSIGNOR TO THE CONLEY FOIL COMPANY, OF NEW YORK, N. Y., A CORPORATION OF NEW JERSEY.

PRINTING-PLATE MATRIX AND METHOD OF MAKING SAME.

1,382,713.

Specification of Letters Patent. Patented June 28, 1921.

Application filed November 6, 1919, Serial No. 336,095. Renewed April 26, 1921. Serial No. 464,570.

To all whom it may concern:

Be it known that I, HARRY M. BLAETZ, a citizen of the United States, residing at Philadelphia, in the county of Philadelphia and State of Pennsylvania, have invented 5 new and useful Improvements in Printing-Plate Matrices and Methods of Making Same, of which the following is a specification.

10 This invention relates to certain novel and useful improvements in matrices and method of making the same, and has particular application to matrices adapted for use in the production of electrotypes.

15 Heretofore in the manufacture of matrices for making printing electrotypes it has been the practice to use a sheet or blank of pure, soft lead for the body of the matrix, inasmuch as the lead, owing to its inherent 20 characteristics of ductility and capability of manipulation, will readily take impressions when subjected to pressure against an original printing plate or die. Therefore, the ordinary operation in making a matrix by 25 what is known as the cold-molding process is to impose a lead sheet upon the printing face of the original type or die and subject the same to pressure in an ordinary press to produce the printing face in the lead sheet.

30 However prior to the molding process, the lead sheet must be subjected to certain operations which are both tedious and expensive, and therefore, from a commercial standpoint there are certain disadvantages incident to 35 the use of the pure lead in the making of electrotype matrices and which disadvantages I overcome by my invention.

40 For example I might state that the operation of preparing a sheet of lead for the matrix molding purposes has always necessitated considerable preliminary work. Lead, owing to its peculiar nature has a tendency to rapidly oxidize on its surface, and this 45 oxidation must be eliminated before the sheet can be used for molding.

Furthermore owing to the extreme softness of the lead sheet the surface is liable to show imperfections, rough spots or pits and the like, due to imperfect rolling in the 50 making of such sheet. Consequently it is usual to brush or clean the impression face of the lead sheet with a wire brush, for the purpose of removing the oxidized particles and the rough spots or pits, and after this 55 has been done the sheet is generally coated

with a solution of benzin and bees wax and then polished with fine graphite. These preliminary operations of preparing the sheet for molding result in the expenditure of considerable time and labor, and as the 60 work must be performed by a skilled workman, it of course increases the expense of making the matrix and electroplate.

With my matrix and the method I pursue in the making of same I obviate all of these 65 operations and conditions in addition to providing a matrix which is far superior to the ordinary lead matrix and which produces a high-grade electroplate.

My invention consists in the matrix, and 70 in the method of making the same set forth in and falling within the scope of the appended claims.

In the drawings I have shown a matrix on 75 an enlarged scale, when thickness is considered, the thickness of the matrix as actually made corresponding to that of the blank shown in Fig. 1.

In the accompanying drawing:

Figure 1, is a perspective view of a blank 80 such as is used for making my matrix,

Fig. 2, is a view partly in section and partly in elevation illustrating the molding of the matrix against the original printing body between the platens of a press, said 85 press platens being merely conventionally illustrated,

Fig. 3 is a cross sectional view of the resulting molded matrix,

Fig. 4, is a cross sectional view of the complete matrix and showing applied thereto a 90 separating coating which is employed to permit the ready separation of the electroplate shell from the matrix after the ordinary electroplating process has been completed.

Referring now to the accompanying drawings in detail, the letter B indicates, as an 95 entirety, the sheet or blank from which the matrix is made. This sheet B is of a composite nature and includes a back or base 100 section 1, which is preferably composed of pure lead, and an impression surface or face section 2 which is made up of an exceedingly thin homogeneous film or skin of pure tin 105 rolled upon and intimately united with the lead base or back 1. The thinness of this tin facing 2, in comparison with the lead back or base 1 will be appreciated when I state that in actual practice I have found a 110

preferable form of composite sheet to be one wherein the ratio of the components of the sheet is one per cent. of tin to ninety-nine per cent. of lead. I prefer to make this tin facing of such skin or foil-like thinness, because were such face of an appreciate thickness it would be too stiff and hard, owing to the inherent characteristics of tin, and a good impression against the original printing plate or die could not be made without resorting to such high pressure as would tend to damage both the matrix being made and the original used in making the matrix. Furthermore as pure lead is ductile and easily worked under low pressure my thin tin facing covering the lead back or base will not appreciably interfere with the manipulation of the lead back under pressure, but on the contrary will flex or bend to respond to the movement of the lead back in the press, thereby taking accurate detail impressions from the original die or plate. As the tin-facing will not oxidize in the manner of lead but will present a bright, clean, highly polished surface, it is not necessary to preliminarily scratch or brush the tin facing nor to polish the same, as must be done in the case of an all lead sheet, and consequently a great saving is obtained in the manufacture of the matrix. Because of its bright, smooth, polished surface I prefer to employ tin for the skin or foil-like facing 2 and have therefore herein mentioned this metal, but I wish it to be understood that the facing may be made of a thin homogeneous skin or foil of any other metal possessing the requisite characteristics which are applicable to tin, that is to say I may employ any metal which when in the nature of a thin foil-like skin will readily respond to pressure so as to make the necessary reproduction, and yet will present a smooth, uniform, highly polished surface which will not readily oxidize and which will not require preliminary treatment.

In making the matrix the original die or printing plate shown at D, the printing surface of which is to be reproduced, is placed on the lower platen P of a suitable press, and the matrix sheet B is imposed upon the die or plate D with the face 2 in contact with the latter. The upper platen P' of the press may then be closed, and under the ordinary or minimum pressure used in the cold molding process the impression may be made and after completion the matrix will appear as shown in Fig. 3.

After the matrix has been made and it is desired to use the same in the production of an electrolyte, the skin-line face 2 of such matrix is coated with a very thin film of a suitable separating agent, shown at 3, preferably a solution of sodium bichromate. Sodium bichromate possesses manifest ad-

vantages as a separating medium because it 65 may be applied in the film so thin that it cannot be measured with a micrometer, and yet it will not wash from the face of the matrix. This film will protect the face 2 from the action of sulfuric acid which is a part of the nickel or electroplating solution, and at the same time, when the electroplate or shell has been deposited in the usual manner, by placing the coated matrix in the electroplating bath for a sufficient length of time, such 70 electroplate shell, after the electroplating process, may be readily separated or removed from the matrix. This electroplate shell when separated from the mold will present the appearance of highly polished 75 nickel, free from flaws, pits and other imperfections and blemishes. This result is obtained because of the character of the skin-like face 2 of the matrix, which face, as before stated does not require the treatment 80 with or the addition of such material as will be liable to cause imperfections in the face.

While I have herein shown and described a preferred embodiment of my invention I wish it to be understood that I do not limit 90 myself to all the precise details herein set forth by way of illustration, as modification and variation may be made without departing from the spirit of the invention or exceeding the scope of the appended claims. 95

What I claim is:

1. A matrix for making printing plates comprising a backing composed of a relatively thick sheet of ductile easily moldable metal and a matrix face mechanically united 100 with said backing and comprising an exceedingly thin film of a relatively hard non-oxidizing metal.

2. A matrix for making printing plates comprising a backing composed of a relatively thick sheet of lead and a molding face mechanically united with said backing and comprising an exceedingly thin film of tin. 105

3. A matrix for making printing plates comprising a backing composed of a relatively thick homogeneous sheet of lead, and a face section intimately united with said backing and comprising an exceedingly thin homogeneous film of tin, said rolled tin face having plate reproducing depressions and 110 elevations therein. 115

4. A matrix for making printing plates comprising backing composed of a relatively thick sheet of lead, a matrix face section united with said backing and comprising 120 an exceedingly thin film of a rolled non-oxidizing metal, and a coating composed of a solution of sodium bichromate covering the matrix face.

5. A matrix for making printing plates 125 comprising a backing composed of a relatively thick sheet of lead, a matrix face intimately united with said backing and com-

prising an exceedingly thin film of rolled tin and a coating of sodium bichromate imposed upon the matrix face.

6. The herein described method of making 5 a matrix for use in the manufacture of printing plates which comprises imposing an exceedingly thin film of a relatively hard non-oxidizing metal upon a relatively thick sheet of ductile metal, placing the composite 10 sheet thus formed with the non-oxidizing metallic face thereof in contact with the plate or die to be reproduced, then subjecting the same to pressure while in such position to reproduce the depressions and elevations 15 of the plate or die face in the non-oxidizing metallic face, then removing the composite sheet and coating the matrix face of the same with a separating agent.
7. The herein described method of making 20 a matrix for use in the manufacture of printing plates, which comprises imposing an exceedingly thin skin of tin upon a relatively thick backing sheet of lead, placing said composite sheet thus formed with its 25 tin face in contact with the plate or die to be reproduced, then subjecting the same to pressure while in such position to reproduce the depressions and elevations of the plate or die face in the tin face, then removing 30 the composite sheet and coating the tin face

of the same with a separating solution of sodium bichromate.

8. The herein described method of making a matrix for use in the manufacture of printing plates, which comprises rolling an 35 exceedingly thin film of a relatively hard non-oxidizing metal upon a relatively thick sheet of ductile metal, placing the composite sheet thus formed with the non-oxidizing metallic face thereof in contact with the 40 plate or die to be reproduced, then subjecting the same to pressure while in such position to reproduce the depressions and elevations of the plate or die face in the non-oxidizing metallic face. 45

9. The herein described method of making a matrix for use in the manufacture of printing plates, which comprises rolling an exceedingly thin section of tin upon a relatively thick backing sheet of lead, placing 50 said composite sheet thus formed with its tin face in contact with the plate or die to be reproduced, then subjecting the same to pressure while in such position to reproduce the depressions and elevations of the plate 55 or die face in the tin face.

In testimony whereof I have hereunto set my hand.

HARRY M. BLAETZ.
